UNITED STATES PATENT OFFICE.

FREDERICK WILLIAM ANDREW, OF BROOKLYN, NEW YORK, ASSIGNOR TO EISEMANN MAGNETO CO., OF BROOKLYN, NEW YORK, A CORPORATION OF NEW YORK.

LOCKING DEVICE FOR IMPULSE-STARTERS.

1,282,010.

Specification of Letters Patent. Patented Oct. 15. 1918.

Application filed June 29, 1918. Serial No. 242,612.

To all whom it may concern:

Be it known that I, FREDERICK WILLIAM ANDREW, a citizen of the United States, and a resident of the city of New York, borough 5 of Brooklyn, county of Kings, and State of New York, have invented certain new and useful Improvements in Locking Devices for Impulse-Starters, whereof the following is a full, clear, and exact specification.

10 My invention relates to devices known in the art as "impulse starters," by means of which a rapid rotatory motion is imparted to the armature of a magneto at the moment of starting an internal combustion engine 15 to produce a spark of sufficient intensity to ignite the explosive charge in the cylinder of the engine. These "impulse starters" comprise, generally, a driven element fixed to the rotatory part of a magneto, a driving element secured to the gear connecting it with the engine, and a spring, set between the driven and the driving elements, so as to be tensioned when the driving element is rotated in advance of the driven one. After 25 the engine has been started, the "impulse starter" operates as a coupling; in some of their constructions the aforementioned spring being utilized also as the connecting means between the driving and the driven 30 elements, in others a separate coupling element is employed for this purpose.

An example of this second method of construction is shown and described in the U. S. Letters Patent No. 1,251,216. In this 35 structure the yoke, designated 21 in the drawings, constitutes the coupling element. It is permanently engaged with the driven element of the impulse starter, and is designed to be moved, by centrifugal force, 40 into, and then held, in engagement with the driving element, when the engine is running, and to drop out of the engagement when the engine slows down or stops running. However, even in this kind of "impulse starters" the functioning of the device, or the 45 ability to perform its function, depends on the spring, and the breaking of the spring renders these devices inoperative, not only for the starting of the engine, but also as 50 means for transmitting rotatory motion from the driving shaft to the shaft of the rotatory part of the magneto, and then the magneto, and the ignition, and consequently also the engine, are put out of action.

55 The object of my invention is to provide

means for enabling a device of this kind to be used as a coupling in case of an accidental breaking of the spring, to start the engine, and to maintain it in operation after having been started.

To this end my invention consists in devising means for enabling the impulse starter to be used as a coupling for maintaining the driving connection when the spring breaks, and in so combining these 65 means with the parts of the impulse starting device that they will not interfere, in any way, with the operation of the "impulse starters" as a starting device as long as it stays in operative condition, and yet be 70 readily available for the stated purpose.

These locking means may be constructed in different ways, largely determined by the varying constructions of the starting devices, upon which they are to be used; the 75 locking devices, illustrated in the accompanying drawings, and hereinafter described, show the principal features of my invention, and the method of its application to an "impulse starter."

In the accompanying drawings, Figure 1 is a perspective view of a locking device, constructed according to my invention;

Fig. 2 is a plan view thereof in position to 85 show the spring latch;

Fig. 3 a sectional view thereof on line 3—3 indicated in Fig. 2;

Fig. 4 is a perspective view of the assembled impulse starter shown and described in the U. S. Letters Patent No. 1,251,216, prepared for applying thereto the locking device;

Fig. 5 is a similar view, showing the locking device applied thereto, and set in inactive position, and

Fig. 6 a similar view showing the locking device in action;

Fig. 7 is a perspective view of a modified form of my locking device;

Fig. 8 a similar view of another modified form of my locking device;

Fig. 9 is a perspective view of an impulse starter, prepared for applying this modified form of the locking device thereto;

Fig. 10 a similar view of the impulse starter with the locking device mounted thereon, and set in action; and

Figs. 11 and 12 are perspective views of an impulse starter, and of another modified

form of my improved locking device shown in plan view in Fig. 13, applied thereto, Fig. 11 showing the locking device in inactive position, and Fig. 12 in active position.

5 The locking device shown in Figs. 1 to 8, comprises the annular band *a* snugly fitted upon the driven member 11 of the "impulse starter" shown and described in the aforementioned U. S. Letters Patent No. 10 1,251,216, and having an aperture *b*, corresponding to the aperture 26 in the annular rim 14 of the driven member; the spring latch, composed of the curved spring *c*, having one end secured, as by rivets *d*, to the 15 band *a*, and the pin *e* set in its other, free end. The pin *e* projects through the aperture *o* in the band *a* and is fitted to enter the bores *e*¹ and *e*² in the annular rim 14 of the driven member. The edge of the band *a*, 20 adjoining the spring latch, is turned to form the narrow flange *a'*, the object of this flange being to maintain the band *a* in the required lateral position upon the rim 14 of the driven member of the "impulse starter," 25 so that the positions of the pin *e* may laterally register with the bores *e*¹ and *e*², and the aperture *b* in the band *a* of the locking device with the aperture 26 in the rim 14 of the impulse starter.

30 In the modified construction of my locking device, illustrated in Fig. 7, the curved spring *c'* is made of a strip cut in the shape of a tongue from the body of the band *a*. This is feasible, in view of the fact, that the 35 band *a* is made of cold rolled sheet steel possessing sufficient resiliency for that purpose.

Both forms of the locking device are applied to the "impulse starter," by setting the 40 band *a* upon the driven member thereof, so that the flange *a'* will abut against the edge of the rim 14, adjoining the driving member when the device is assembled. The locking device is then turned on the driven member 45 until the aperture *b* in the band *a* registers with the aperture 26 in the rim 14 of the driven member. When the locking device is set in this position, the pin *e* snaps into the bore *e*¹ in the rim 14 of the driven member 50 and prevents shifting of the band *a* in either direction. This is the inactive position of the locking device.

When it is to be set in action, the end of the curved spring *c*, which is set to lie closely 55 to the band *a*, is raised, thereby withdrawing the pin *e* from the bore *e*¹ and the driven member 11 is turned to the left, while the band *a* is held against turning with it, until the pin *e* snaps into the bore *e*². In this 60 position the band *a* covers the aperture 26 in the rim 14 of the driven member 11 of the impulse starter, and holds the coupling member 21 within, and in engagement with the driving member, preventing its dropping out of the engagement when the "im-

pulse starter" is turned, while the engine stands still. This also prevents the coupling member from engaging with the catch-plate 31, or other means for holding the driven member against rotating.

70 In the modified construction, illustrated in Figs. 8, 9 and 10, the slot *h* in the band *a* and set-screw *i*, are substituted for the spring latch *c* and pin *e* of the construction illustrated in Fig. 1, and a screw-threaded bore *i'*, in the rim 14 of the driven member 11, for the bores *e*¹ and *e*². The set-screw *i* passes through the slot *h* and is fitted into the screw-threaded bore *i'*; its object is to limit the shift of the band *a* upon the rim 80 14 of the driven member 11, and to fix the position of the band *a* thereon. To move the locking device from its normal, inactive position, in which the aperture *b* in the band *a* registers with the aperture 26 in the rim 14 of the driven member 11, the set-screw *i* is loosened, the band *a* shifting to the position shown in Fig. 10, and then the screw *i* tightened. By thus shifting the band, the aperture 26 in the rim 14 of the driven member 90 11 of the impulse starter, is covered, and the coupling member 21 of the impulse starter is held in engagement with the driving member 15, whereby the driven and the driving members are permanently coupled. 95

The locking device, illustrated in Figs. 11, 12 and 13, is made in the form of a spring turn-bolt *k*, turnably secured by the set-screw *m* to the rim 14 of the impulse starter, in position to cover the aperture 26 to hold the coupling device, when set as shown in Fig. 12. The set-screw *m* passes through a perforation in the base of the locking device *k* and engages in a correspondingly screw-threaded bore in the rim 14 of the driven member 11 of the impulse starter. The rear end *k'* of the turn-bolt *k* is bent up at an approximately right angle to its base, and the portion *n* of the rim 14 is flattened to facilitate the operation of shifting, or turning the bolt *k* from its inactive position (shown in Fig. 11) to its active position shown in Fig. 12. When the bolt *k* is set in this position it closes the aperture 26 in the rim 14 of the impulse starter, and prevents 105 the reciprocally movable coupling device 21 from dropping out of its engagement with the driving member 15, thus maintaining the rigid coupling engagement of the driven with the driving member, and enabling the 110 impulse starter to operate, permanently, as a coupling, transmitting the rotatory motion from the engine shaft to the magneto. It also prevents the trigger 22 of the coupling device 21 from engaging with the catch- 115 plate. 120

I claim as my invention:

1. The combination with an impulse starter, comprising a driven and a driving member and a movable coupling device, 125 130

adapted to be moved in position to rigidly connect the driven and the driving member, of a locking device, movably mounted thereon, and adapted to be set to hold the coupling device in the position rigidly connecting the driven with the driving member; substantially as herein shown and described.

2. The combination with an impulse 10 starter, comprising a driving and a driven member, and a reciprocally movable coupling device, adapted to join the driven and the driving members together, when moved in one position; of a locking device, 15 turnably mounted on the impulse starter, and adapted to be set to hold the coupling device permanently in its position, coupling the driven and the driving members together; substantially as herein shown and described.

3. The combination with an impulse 20 starter, comprising a driven and a driving member and a movable coupling device, adapted to be moved in position coupling the driven member with the driving member, of a manually operatable locking device, movably mounted on the impulse starter,

adapted to be set in active or inactive positions, and means for fixing it in either position, the said locking device, when set in active position, holding the coupling device fixedly in the position, coupling together the driven and the driving member; substantially as herein shown and described.

4. The combination with an impulse 25 starter, comprising a driving and a driven member, a reciprocally movable coupling device, permanently engaging with the driven member, and means thereon, and on the driving member, adapted to interlock 30 when the coupling device is moved to effect its engagement with the driving member, thereby coupling the driven and the driving members together; of a locking device, turnably mounted on the driven member and 35 adapted to be set to hold the coupling device permanently in engagement with the driving member; substantially as herein shown and described.

FREDERICK WILLIAM ANDREW.
